UNITED STATES PATENT OFFICE.

JOHN H. HUNT, OF DETROIT, MICHIGAN, AND JOHN T. FITZSIMMONS, OF ANDERSON, INDIANA, ASSIGNORS TO DELCO-REMY CORPORATION, OF DAYTON, OHIO, A CORPORATION OF DELAWARE.

LIGHTING AND IGNITION APPARATUS.

Original application filed January 21, 1925, Serial No. 3,732. Divided and this application filed March 11, 1927. Serial No. 174,478.

This invention relates to electrical lighting and ignition apparatus for automotive vehicles, such as light delivery trucks which do not carry a storage battery and motor for starting the engine.

This application is a division of Patent No. 1,641,434 issued Sept. 6, 1927, to J. H. Hunt and J. T. Fitzsimmons.

Patent No. 1,638,307, issued August 9, 1927, to John H. Hunt, discloses an electrical lighting and ignition system including a generator comprising a field magnet having pole face windings in which lighting current is generated, and a single rotor for generating an alternating current for ignition purposes. It is necessary that this generator be driven by the engine in fixed relation therewith. This type of apparatus requires a gear or chain and sprocket drive between the engine and the generator and cannot be belt driven.

One of the objects of the present invention is to provide an electrical system of the type referred to but including a generator having pole face windings and a single rotor for generating lighting and ignition currents and which may be belt driven by the engine. Consequently this generator may be used interchangeably with a conventional type of belt driven direct current generator used on automobiles for charging the storage battery. This object is accomplished by providing a generator with a drum wound armature from which direct current is commutated for ignition purposes.

A further object is to minimize the fluctuations in the armature voltage and this is accomplished by a particular arrangement of the pole face teeth with respect to the armature core teeth.

A further object of the invention is to provide for the regulation of the ignition current in an ignition system including an induction coil and a generator of the type referred to.

A further object is to provide for protection of the lighting circuit including the pole face winding in case of accidental short circuiting of the generator armature.

Further objects of the present invention will be apparent from the following description, reference being had to the accompanying drawings, wherein a preferred form of

embodiment of the present invention is clearly shown.

In the drawings:

Fig. 1 is a wiring diagram of the present invention.

Fig. 2 is an elevation of the brush structure of the machine.

Fig. 3 is a fragmentary view looking in the direction of the arrow 3 in Fig. 2.

The details of the frame of the dynamo 20, shown diagrammatically in Fig. 1, are completely disclosed in the original application referred to, but are omitted herein except for the fragmentary showing in Figs. 2 and 3. It will be understood that the frame of the dynamo supports an armature shaft 28 which carries an armature 30 and a commutator 31. The armature 30 is drum wound but differs from the ordinary direct current drum wound armature, in that the core teeth are relatively narrow and the ratio of copper and core iron is higher than shown in the conventional types. The dimensions of the armature which have been found satisfactory are as follows: diameter 2.8 inches; length 3 inches; 18 core slots; one coil per slot having 12 turns of #19 wire; each coil surrounds 8 teeth; and the armature core teeth are $\frac{3}{16}$ of an inch wide at the tip. In Fig. 1, the armature core teeth are designated by numeral 32, and the windings each by numeral 33.

The pole pieces or stator poles 40 and 41 are laminated, the laminations being secured together by rivets 42. The laminations are attached to non-magnetizable rings, one of which is indicated by numeral 43, by means of bolts 46 which pass through the rings and laminations. The pole face teeth 50, 51, 52 and 53 of the pole piece 40 are located in a certain relation to the pole teeth 54, 55, 56 and 57 of the pole piece 41, and in a certain relation to the armature core teeth 32 as will be explained later. The pole pieces 50 to 57 inclusive are surrounded, respectively, by pole face windings 60 to 67 inclusive. The windings 61, 62, 63, 65, 66 and 67 are connected so that their E. M. F.'s will be cumulative and are connected with end terminals 68 and 69, and a center terminal 70. Each of the coils in this series has 25 turns of #17 S. C. E. wire and the current generated therein is used to supply lighting current for the head lamps

72 and 73. The windings 60 and 64 are connected in series so that the E. M. F.'s are cumulative. One end of this series of windings is connected with a terminal 74 and the other with a terminal 75. Each of these windings 60 and 64 has 140 turns of #29 S. C. E. wire and the current generated therein is used for operating lamps of smaller candle power indicated at 76 and 77. These lamps

19 may be the cowl and tail lamps of the vehicle.

The field is excited by a permanent magnet 80 of the horseshoe type. The poles of the magnet are formed with accurate cylindrical faces 81 and 82 for fitting closely around the outer cylindrical surface of the groups of laminations, comprising pole pieces 40 and 41. A resistance element 88 is connected with an insulated or non-grounded commutator brush 90 and a grounded commutator

20 brush 91.

The mounting of the brushes is shown in Figs. 2 and 3. A box type brush holder 92 is attached to a non-conductor 93 which is secured by rivets 94 to a wall 95 of one of the 25 dynamo end frames. The brush indicated at 90 in Fig. 1 includes two brush elements 90^a and 90^b for a purpose to be described later. One of the brush elements, such as 90^a, is a carbon brush relatively high in resistance, 30 and the brush 90^b is a metal relatively low resistance brush. The brushes 90^a and 90^b are connected by pigtails 97 with a terminal 98, and are engaged by brush springs 99^a and 99^b, respectively, having their ends fixed to a 35 portion 100 of the brush holder 92. The brush holder 92 cooperates with a spacing element 101 tending to maintain the brushes 90^a and 90^b spaced from the non-conducting plate 93.

40 The pressure exerted by the brush spring 99^a is sufficient to maintain the carbon brush 90^a in good electrical contact with the commutator throughout the speed range of dynamo operation, but the pressure exerted 45 by the spring 99^b is sufficient only to maintain the heavier metal brush 90^b in good contact with the commutator at relatively low engine speeds. The other brush 91 indicated in Fig. 1 includes elements 91^a and 91^b corresponding, 50 respectively, to the brush elements 90^a and 90^b. The brush holder 102 of the brush 91 is mounted directly upon a plate 103 which is attached to the end wall 95 by screws 103^a.

55 The commutator and brushes are enclosed by a cup shaped frame extension 110 provided with openings 111 to provide access to the brushes and commutator. These openings are covered by a cover band 112 secured by bolt 113 and nut 114.

60 Referring to Fig. 1 the dynamo brush 90 is connected by wire 120 with ignition coil primary winding 121 which is connected by wire 122 with a switch contact 123. The ignition coil secondary 124 is connected with wire 122

65 and with distributor 125 for distributing

sparking impulses to the spark plugs 126. Wire 122 is connected with a timer 127 operated by the engine. The dynamo terminal 70 is connected by wire 128 with switch contact 129 which in turn is connected by dimmer 70 resistance 130 with switch contact 131. Dynamo terminal 74 is connected by wire 132 with switch contact 133 connected by wire 134 with contact 135. It is obvious that the connection of the switch contact 128 with a 75 grounded contact 136 by a movable contact 137 will cause the timer 127 to be short circuited. Consequently the ignition will be rendered inoperable and the engine will stop. When the contact 137 is in the position shown 80 in Fig. 1, the timer 127 is operative to control the energizing and discharging of the ignition coil which is supplied by current generated in the armature 30.

The lighting circuits are controlled by a 85 movable grounded switch contact 138 which is adapted to connect either contacts 133 and 129, or contacts 135 and 131. If the contact 138 is in position to connect contacts 133 and 129 the lamp 72 will be connected with a 90 group of pole face windings through the following circuit: lamp 72, terminal 69, windings 67, 66 and 65, terminal 70, wire 128, contact 129, contact 138 and a ground return to the lamp 72. Likewise the lamp 73 will be 95 connected with a group of pole face windings through the following circuit: lamp 73, terminal 68, windings 61, 62 and 63, terminal 70, wire 128, contacts 129 and 138, and a ground return to the lamp 73. The tail and cowl 100 lamps 76 and 77 will be connected with a group of pole face windings through the following circuit: lamp 77, lamp 76, terminal 75, pole face windings 64 and 60, terminal 74, wire 132 and contacts 133 and 138 and a 105 ground return to the lamp 77. To dim the head lamps 72 and 73, the switch contact 138 is moved to connect contacts 131 and 135. The head lamp circuit is changed from that described only by introducing the resistance 110 130 in series with lamps 72 and 73. The lamps 76 and 77 will burn as before since the circuit in these lamps has been changed only by the introduction of wire 134 and contact 135. In case one of the head lamps burn out 115 the other lamp will continue to burn since each head lamp is connected with a set of pole face windings.

In case of short circuit of the armature during the operation of the engine, the voltage of the pole face windings will be automatically regulated so that the voltage will not be excessive to cause the lamps to burn out. Referring to Fig. 1 the arrow 140 indicates the direction of rotation of the armature 30. The pole windings 60 and 64 which supply the tail lamps 76 and 77 which are of relatively low candle power, are placed on the leading pole teeth 50 and 54. The short circuiting of the armature will produce ar- 125

130

mature reaction upon the dynamo field in such a manner as to crowd the flux toward the trailing pole teeth and away from the leading pole teeth, therefore, the voltage generated by the 5 windings 60 and 64 will be automatically limited to a safe value for the lamps 76 and 77. This armature reaction will tend to pull the field flux threading the armature from the pole tooth 51 and toward the pole 53 and 10 away from the pole 55 and toward the pole 57, but the total flux in the poles 51, 52, 53, 55, 56 and 57 will be substantially the same so that the total E. M. F. generated in the group of windings 61, 62, 63 or the group of windings 15 65, 66 and 67 will not be substantially higher than before the short circuit occurred. Hence voltage of the current delivered to the head lamps 72 and 73 will not become excessive due to the armature short circuit while the 20 engine is running.

One of the important features of the present invention is that of arranging the pole teeth with respect to the armature core teeth so that the fluctuation in armature voltage 25 will be minimized. As disclosed and claimed in the copending application of John H. Hunt referred to, it has been found advantageous in machines of this type to make the spacing of adjacent field pole teeth one and one-half 30 times the spacing of the armature pole teeth. There is not a complete circle of pole teeth as it is necessary to omit some of the teeth to provide a zone of commutation of the armature. If a direct current armature is used 35 and the teeth are arranged so that the windings of one pole are in phase with the windings of the other, there will be such a fluctuation in voltage of the direct current windings as to cause the possibility of low speed ignition failure if the contacts open when the 40 armature current is too small to produce a spark. It has been found, however, that by shifting the pole pieces the same amount toward the symmetrical axes of the machine 45 in order to bring the windings of the poles out of phase with each other, the fluctuation of armature voltage will be substantially reduced and a higher average attained. Satisfactory results have been obtained when the 50 windings of one pole are out of phase with the windings of a pole of opposite sign by from 90 to 180 electrical degrees. For example, if the armature core has 18 teeth, the cycle of the alternating current occurs every 20° of 55 rotation of the core. The polar projection defined by the groups of teeth 50 to 53, and 54 to 57 should be displaced from 5° to 10° from the conventional arrangement. In Fig. 1 lines $x-x$ and $y-y$ are used to designate 60 the axes of the polar projections, and it will be noted that these axes are displaced about 10°.

When a direct current machine of this type is operating at variable speed throughout the speed range there is a wide variation of armature

voltage. The voltage must be high enough to provide ignition current when cranking the engine by hand. On the other hand it is necessary to limit the current of the ignition coil to a safe value when the 70 engine is operating at high speed. To accomplish this, the inductance of the ignition coil is relatively high. A coil having an inductance of 100 mh. has been found satisfactory. The resistance of the coil should be as low as 75 possible consistent with good manufacturing products, since it is necessary that the resistance of the ignition circuit be low in order to obtain sufficient current for ignition at low engine speed. The coil inductance determines 80 the resistance to some extent. For example, a primary coil resistance of .75 ohm has been found satisfactory. The armature resistance should be as low as possible in order to obtain the maximum current at low engine speed. 85 The resistance of the armature circuit for an armature having dimensions given in the example is about .65 ohm and this resistance includes the resistance of the brushes and the lead wires as well as the armature coils. To 90 obtain the required coil inductance and low resistance the primary coil 121 may have 250 turns of #18 wire.

The resistance 88 across brushes 90 and 91 is for the purpose of absorbing self-inductance of the armature windings when the breaker points of the timer 127 open. This self-inductance may also be absorbed by a condenser connected with the brushes 90 and 91.

At low engine speeds the heavier metallic and low resistance brush elements 90^b and 91^b remain in good electrical contact with the commutator 31 so that the resistance of the armature circuit at low speeds will be relatively low. However, for commuting during higher speeds of the engine the higher resistance carbon brushes have been found more satisfactory since they can be maintained in good electrical contact with the commutator 105 without the excessive pressure required by the metal brush, and metal brushes would permit undesirably high short circuit current in the armature coils short circuited by the brushes at the higher engine speeds. The 110 springs 99^a are adjusted so that the high resistance brush elements 90^a and 91^a will be maintained with good electrical contact with the commutator at all dynamo speeds, but the pressure exerted by brushes 99^b will not be 115 sufficient to maintain the heavier metal brushes 90^b and 91^b in contact with the commutator at the higher engine speeds.

The generator constructed in accordance with the example given will produce satisfactory ignition at 100 R. P. M. and satisfactory operation at 400 R. P. M. or greater of two 6.3 volt, 21 c. p. lamps, and two 6.3 volts 2 c. p. lamps.

A dynamo constructed in accordance with 130

the present invention can be used interchangeably with the conventional types of D. C. generator used in two-unit automotive electric systems, without requiring any change in the 5 manner of mounting upon the chassis or engine frame. This makes the system particularly adaptable to present methods of interchangeable manufacture. The greater demand at present is for the two-unit system, 10 but the demand for an electrical lighting and ignition system without storage battery can be supplied immediately because the generator of the present invention can be installed in place of the usual battery charging generator, and the timer and distributor of the 15 present system can be the same as the apparatus used generally in battery ignition systems.

While the form of embodiment of the present 20 invention, as herein disclosed, constitutes a preferred form, it is to be understood that other forms might be adopted, all coming within the scope of the claims which follow.

What is claimed is as follows:

25 1. An electrical generator having a commutator and a pair of brushes for engaging the commutator, one brush of a pair being of lower electrical resistance than the other, and means for maintaining the low resistance 30 brush in good electrical engagement with the generator commutator only at the lower speeds of the generator and for maintaining the high resistance brush in good electrical engagement with the commutator throughout 35 the speed range of generator operation.

2. An electrical generator having a field

and pole face windings for generating current, and a toothed rotor carrying other generating windings, the pole face windings being so constructed and arranged that in case 40 of accidental short circuit of the rotor windings, the current in the pole face windings will not be excessive.

3. An electrical generator having a plurality of toothed field pole pieces, pole face windings surrounding the leading pole teeth and connected cumulatively for supplying current to a work circuit, said windings each being formed of a relatively large number of turns of relatively high resistance wire, other 45 pole face windings surrounding the other pole teeth and connected cumulatively for supplying current to a second work circuit and each formed of turns of wire fewer in number than the turns of the first mentioned 50 pole face windings and of lower resistance than the wire of the first mentioned pole face windings, and a toothed rotor carrying other generating windings.

4. An electrical generator having a plurality of field pole pieces, a plurality of sets of generating coils carried by the pole pieces, one set having coils located only adjacent the leading portions of the pole pieces, and the other set having coils distributed over the remaining portions of the pole pieces, and a toothed rotor carrying other generating windings.

In testimony whereof we hereunto affix our signatures.

JOHN H. HUNT.

JOHN T. FITZSIMMONS.
